SHOOTING AND CAP EXPLODING TOY GUN

Alfred E. Brandon, New York, N. Y.

Original application March 21, 1938, Serial No. 197,161. Divided and this application May 26, 1939, Serial No. 275,866

7 Claims. (Cl. 124—2)

This application is a division of application No. 197,161; filed March 21, 1938.

This invention relates to toy guns for target practice combined with sound producing device, and more particularly to guns provided with elastic strips, band or spring; and the objects of the invention are:

1. To make new and novel provision for supporting projectiles upon the gun and which affords means for various sizes and shapes of shots to be easily and rapidly placed upon the gun and conveniently used.

2. To facilitate novel means whereby projectiles of various forms and weights can be securely held in position upon the gun and are accurately projected to where desired.

3. To make novel provision for mounting ends of elastic springs above the barrel of guns and which affords means to increase accuracy in target practice, also protect the usefulness of the elastic.

4. To make new and novel provision for supporting the elastic spring intermediate both ends upon the gun and which affords means for snapping the elastic, whereby the velocity of projectiles discharged from the gun is greatly increased.

5. In the novel provision of sound emitting devices to associate with means embodied in the gun so that a desired sound can be produced when the gun is discharged; and one such device is a new kind of anvil intended to be used for exploding caps with or upon the gun.

Fig. 1 is a side view of the gun, and shows the position, after the gun has been discharged, of the parts and wherein the elastic band or strip is broken off at several portions.

Fig. 2 is a side elevational view of the gun shown in Fig. 1, but when it is loaded, and portions of which are broken off and shown sectionally.

Fig. 3 is a plan view of the gun when it is loaded, but the elastic band or strip is broken off from one side of the gun to show the position the spring, engaging the elastic strip or band thereat, assumes when the gun is fired.

Fig. 4 is a vertical sectional view on the line 4—4 of Fig. 3.

Fig. 5 is an enlarged sectional view taken on line 5—5 in Fig. 1.

Fig. 6 is an enlarged sectional view on the line 6—6 in Fig. 1.

Fig. 7 is an enlarged sectional view on the line 7—7 in Fig. 1.

Fig. 8 is a fragmentary longitudinal vertical

sectional view of a modified form of the gun constructed according to the invention.

Fig. 9 is a transverse vertical sectional view along the line 9—9 of the gun shown in Fig. 8.

Fig. 10 is a longitudinal vertical sectional view of Fig. 5, showing a modification of said part embodied in this invention.

One form of the gun shows the body, which comprises the barrel 1, the stock 2 and butt or handle 3, is made of wood or of light composition element. The stock is provided with a suitable slot 4, for housing a trigger 5, having its fulcrum on a pin 6, and a resilient spring 7 which is secured on one end by a screw 8 against the wall portion 4a of the slot, the other end slidably engaging the same wall portion. It will be noted that the trigger 5, lower portion 5a serving as finger portion, moves slidably against the spring 7 which in turn urges the finger portion 5a against the wall portion 4b of the slot where the trigger is checked to normal position.

This trigger 5 is provided with a horizontal sear 5b, having a pin 9 which projects in a longitudinal recess 10, formed in the upper side of the stock. This recess is shown to be of dovetail in transverse section and therein is housed and freely moves a carriage 11, having an aperture 12 in engagement with the pin 9; thus, the carriage is locked in position against the rear end of said recess lower portion and also against the upper portion 13 thereof which is in the form of a projection over said recess.

It will be noted, that the carriage is provided with a groove 14 which functions to guide the pin 9 into the aperture 12, and a projection 15 rearwardly of said carriage engages the upper portion 13 prevents forward tipping of the upper portion 16 of the carriage, and also tends to protect the side walls of said recess 10 from splitting thereat when the elastic band or strip is tense.

Said upper portion 16 is constructed with an aperture 17 for housing the rear end of the elastic band or strip 18, and a pair of spaced parallel lugs 19 for supporting a claw element 20 which is pivotally mounted upon a bolt or rivet 21 connecting the lugs. This claw element having one end engaging an upstanding element 22 when the other end holds a projectile 23, which may be of various shape and size, in the carriage independently of the elastic band or strip, as is evident from the drawing. The contact point between the upstanding element 22 and claw element 20 may be provided with suitable spring means at 24 capable of taking up any slack which may occur between the fore end of the claw 55

element and projectiles of various sizes. And 25 are screws or nails which secure the element 22 on the stock in alignment with the recess.

Obviously, the bolt 21 may be taken out to remove the claw 20 when it is desired to use extra size of projectiles on the gun; or the element 22 may be removed in such instances instead of the claw element 20.

On the front of the barrel is a post element 10 26 for mounting thereon a pocket element 27, which is adapted to receive the front end of said elastic strip or band. This pocket element 27, preferably pivotally connected as shown in the drawing, is adapted for engaging a wedge-shaped 15 bolt 28, having end portion 29 threaded to receive a nut 30, which tends to draw the bolt 28 forward; thus, with the ends or end of the elastic 18 in the pocket element, the nut 30 may be manipulated sufficiently to press the said ends 20 or end against the interior walls of the pocket element 27 and wedge-shaped bolt 28.

It will be noted, that the upper side of the barrel 1 is a distance below the upper side of the stock 2 sufficiently for the upper side of the 25 pocket element 27 to be below the upper side of the stock for clearance for projectiles, which are discharged from the gun. And also, for mounting thereon a housing 31 for a spring element 32, both of which are secured by bolt or 30 screw 33 on the barrel.

This spring element 32 having its longitudinal axis in vertical alignment with that of the device and comprising a pair of outwardly spread wings 32a and 32b, each of which having pockets 34 for engaging either side of the elastic 18. These wings normally diverging from one another, and their upper portions are in a twisted 35 position, see Fig. 3. Obviously, when the gun is being loaded, the elastic sides sliding against the 40 wall of each pocket 34 force the wings toward each other so that the pockets are positioned substantially in parallel relation when the gun is loaded and, when the gun is discharged, the elastic being snapped or stressed by the wings laterally and substantially downward in respect of 45 the gun, thereby force the carriage to slide against the bottom of the recess 10 rather than against the sides thereof. It is of course understood that I can make a spring element 32 to 50 direct said carriage otherwise in said recess; and one way is to dispose the spring element with its longitudinal axis angularly rather than horizontally with the longitudinal axis of the gun.

35 is an anvil mounted on the front end of the 55 recess 10, and it is secured by a screw or bolt 38. This anvil having a pocket 37 for receiving caps of the ordinary type, and an aperture 38 which is in alignment with one such cap (not shown) deposited in the pocket 37.

60 39 is a hammer slidably engaging the recess. This hammer having a projection 40 adapted to freely engage the aperture 38; and a compression spring 41 normally positions the hammer 39 and the projection 40 in alignment with the anvil 35 65 and its aperture 38. Thus, when the gun is discharged the carriage, traveling longitudinally in the recess, will strike against the hammer 39 and thereby drive the projection 40 through the aperture 38 sufficiently to cause to explode a previously deposited cap in the pocket 37, and the 70 spring 41, acting as a shock absorber, restores the hammer 39 to normal position.

Having described and illustrated the parts and assembly thereof of the above form; the modification constructed according to the invention

and shown in Figs. 8 and 9 will be readily understood.

In this modification, the body of the gun 42 is of wood for the lower portion and the upper portion of the stock is of metal pressed to form 5 a shell or casing 43, secured by nails or screws 44 to the wood portion of the gun.

The metal shell or casing carries a recess 45, being for sake of simplicity, similar in transverse section to the one shown in the previous figures 10 for housing the carriage 46, which is provided with a projection 47 adapted to project into the aperture 48 of the anvil 49 to explode caps previously deposited in the pocket or chamber 50, as already described. 15

The rear projection 51 of the carriage engages the projection 52 of the shell or casing 43. And its upper or vertical portion 53 fore portion 54 may be provided with a flexible spring element 20 to function as claw element.

56 is a projectile of irregular shape and it is shown in dotted lines; and the flat spring 55 is also shown in dotted lines to illustrate the position it assumes when in engagement with a projectile as such. This spring 55 may be detachably mounted upon the upper portion 53 to retain projectiles of any size for practical use. 25

It is of course understood, that I can construct the lower horizontal portion of the carriage in the form of a curve in transverse section and, a 30 recess on the body of the gun adaptable to be engaged by such a lower portion of said carriage.

In Fig. 10, it will be noted that I provide female threads on the wedge-shaped bolt 28a for engaging a bolt 58, thereby clamping the ends of 35 the elastic band or strip 18a against the inner walls of the pocket element 27a, as previously described.

It is of course understood, that I can make the bore of said wedge-shaped bolt 28a without 40 threads and extend said bore from end to end of said bolt 28a for said bolt 58 to pass therethrough to engage a nut, which will cause the wedge-shaped bolt 28a to function as already described. 45

In the drawing and specification there has been set forth a preferred embodiment of the invention, and although specific terms are employed, they are used in a generic and descriptive sense only, and not for purposes of limitation, 50 the scope of the invention being set forth in the appended claims.

And I claim as new:

1. A shooting and cap exploding toy gun comprising a stock and barrel, guide means on top of the barrel, a carriage and striker mounted on the guide means, the carriage adapted to carry missiles of various size and shape above the gun, said guide means engaging the lower portion of the carriage, cooperating means on said lower portion and said guide means respectively, said cooperating means including a projection on one end of said guide means and an extension rearwardly of said lower portion adapted to engage below the projection and thereby prevent forward tipping movement of the upper portion of said carriage at said end, said lower portion formed to provide an aperture therein and trigger means mounted for engagement with said aperture for holding said carriage against said end, and an anvil mounted upon said barrel in the path of said striker whereby a cap may be exploded by impact and movement of said striker and carriage will be checked. 70

2. A gun as claimed in claim 1 including 75

clamping means mounted on said carriage for retaining the missiles thereon, said clamping means comprising a lever element and means pivotally mounting said lever on the carriage, 5 means mounted on the stock for engaging an end of the lever element thereby moving the opposite end of said lever into gripping engagement with a missile.

3. A gun as claimed in claim 1 wherein the upper portion of said carriage is formed to provide an aperture, an elastic element in said aperture, clamping means adjacent the opposite end of said barrel releasably holding said element therein, means pivotally securing said clamping 10 means to said barrel, guide means pivotally mounted upon said barrel between the carriage and the clamping means, said guide means engaging said elastic element thereby guiding the path of travel thereof.

20 4. A gun as claimed in claim 1 including an elastic band attached at its ends to the forward portion of the barrel to provide a loop portion, said loop slidably engaging said carriage, spring means pivotally mounted on said barrel between 25 the points of attachment of said band to the carriage and barrel respectively, said spring means including a pair of arms in relatively diverging relation, each arm engaging the band on opposite sides of the looped portion whereby retraction of the band will tension the spring means.

5. A gun as claimed in claim 1 wherein said anvil comprises an element formed to provide a vertical chamber and a slot laterally of said chamber for the insertion of a cap, said element being further formed to provide an aperture communicating with said chamber to accommodate said striker to detonate a cap placed within said chamber.

6. A shooting and cap exploding toy gun comprising a stock and barrel, guide means on top of the barrel, a carriage and striker mounted on the guide means, said carriage adapted to carry objects of various size and shape above the gun, 5 said guide means engaging the lower portion of said carriage, cooperating means on said lower portion and said guide means respectively, said cooperating means including a projection on one end of said guide means and an extension rearwardly of said lower portion adapted to engage below the projection and thereby prevent forward tipping movement at the upper portion of said carriage at said end, said lower portion formed to provide an aperture therein and trigger 10 means mounted for engagement with said aperture for holding said carriage against said end, an anvil mounted upon said barrel at the other end of said guide means, and striker means in the path of travel of the carriage associated with 15 said anvil, said striker means being mounted for movement longitudinally of the guide means in the travel path of said carriage, said striker means thereby contacting said anvil upon impact by said carriage to check movement of the carriage. 20

7. A gun as claimed in claim 6 wherein said anvil is formed to provide a chamber for the reception of a cap and further formed to provide an aperture communicating with said chamber, 30 and wherein said striker is positioned in said aperture and a spring is interposed between the anvil and striker whereby said spring may resiliently check the forward movement of the carriage and at the same time permit the striker 35 to fire a cap in the chamber.

ALFRED E. BRANDON.
